DESIGN FOR A TOY DRESSING TABLE OR THE LIKE

Jacob Pressman, New York, N. Y.

Application February 17, 1942, Serial No. 105,841

Term of patent 14 years

To all whom it may concern:

Be it known that I, Jacob Pressman, a citizen of the United States, and a resident of the city of New York, Borough of Manhattan, in the county and State of New York, have invented a new, original, and ornamental Design for a Toy Dressing Table or the like, of which the following is a specification, reference being had to the accompanying drawing, forming part thereof, in which—

Fig. 1 is a perspective view of a toy dressing table or the like, showing my new design;

Fig. 2 is a top plan view of the toy dressing table; and

Fig. 3 is a rear elevational view of the toy dressing table.

I claim:

The ornamental design for a toy dressing table or the like, substantially as shown.

JACOB PRESSMAN.
